UNITED STATES PATENT OFFICE

WILBUR H. ARMACOST, OF NEW YORK, N. Y., ASSIGNOR TO THE SUPERHEATER COMPANY, OF NEW YORK, N. Y.

REHEATER

Application filed January 28, 1930. Serial No. 423,966.

My invention relates to the art of heat exchange and aims to provide a heat exchanger having high capacity per unit volume and which is both convenient to install and economical to manufacture.

5 The two-pass heat exchanger is a well known piece of apparatus and in its usual form includes a shell having an internal partition forming two passes, one of which contains tubes for heating fluid. This type of apparatus although preferred for certain conditions has been found to suffer from heat transfer through the internal partition from the hot fluid to the cold.

10 15 It is an object of my invention to provide means in a two-pass heat exchanger which shall substantially eliminate the difficulty just mentioned.

A further object of my invention is to provide 20 compact arrangements of the heating tubes of heat exchangers.

Still another object of my invention is to provide tube units for heat exchangers adapted for ready insertion and removal from the 25 apparatus when desired.

The novel features of my invention are pointed out in the appended claims. The invention itself, however, together with further objects and advantages, will best be understood from a detailed description of a specific heat exchanger embodying the invention, and such a description will now be given in connection with the accompanying drawings in which

25 Fig. 1 is a central longitudinal section through a two-pass exchanger in accordance with my invention.

Fig. 2 is a fragmentary sectional view of the upper portion of the apparatus shown in 40 Fig. 1 and taken on a vertical plane including line 2—2 of Fig. 3.

Fig. 3 is a sectional plan of the apparatus illustrated in Fig. 1, the left half of Fig. 3 being taken on a plane in the upper part of 45 the apparatus and the right hand half of Fig. 3 being taken on a plane through the inlet and outlet.

Fig. 4 is a fragmentary horizontal section 50 illustrating one manner of bracing the tube units of Fig. 1 against lateral movement.

Fig. 5 is a fragmentary vertical section illustrating the manner of attaching the tubes of a unit to a vertical hanger.

Fig. 6 is a fragmentary vertical section on the same plane as Fig. 2 of a portion of the 55 apparatus of Fig. 1 and illustrating the bottom support for the tube units and the lower end of a dead space.

The illustrative embodiment of the invention shown in the drawings is a steam reheat- 60 er of the well known two-pass type and shown as having its axis vertical with the inlet and the outlet for the steam to be heated placed at its lower end. The shell of the heat exchanger is indicated at 14 and the inlet and 65 outlet are at 16 and 18 respectively. The inlet is separated from the outlet by an interior partition 20 running upwardly from the bottom of the shell 14 and forming an upward pass 22 and a downward pass 24 connected at 70 their upper ends. A bundle T of coiled heating tubes is shown substantially filling the pass 22, and headers 26 and 28 are provided for supplying heating fluid such as super- 75 heated steam to and receiving such fluid from the coils in bundle T. As shown, the headers 26 and 28 are inserted into the lower portion of the pass 22 through the shell 14, the outer ends of the headers projecting through the shell and having flanges 30 threaded thereon 80 for positioning the headers and contacting with the faced fittings 32 for this purpose, the fittings 32 being fixed to the shell 14. The inlet and outlet ends of the serpentine sections 36 are detachably secured to the head- 85 ers 26 and 28 by a suitable means 66.

It will be seen that the ingoing and outgoing streams of fluid on opposite sides of the partition 20 have different temperatures at any given level so that there has been a transfer of heat from the outgoing to the ingoing stream through the partition of a two-pass heat exchanger, reducing the volumetric and the commercial efficiency of the apparatus. It is a feature of the present invention to 95 minimize such a transfer of heat to the ingoing fluid by running the inlet sections 34 and 34a of the tubes in the bundle T from the inlet header 26 along the partition to heat it. As illustrated, the inlet sections 34 and 34a 100

of the tubes in bundle T spread across the entire width of partition 20 and run upwardly adjacent the partition for almost its entire length thereby maintaining the partition at a temperature at least as high as that of the outgoing fluid and effectively preventing transfer of heat from the outgoing to the ingoing fluid.

It is a feature of the invention to build up a tube bundle T of units of substantially the same size and so arranged as to be conveniently assembled and removed from the apparatus. For this purpose, the partition 20 is curved in a horizontal plane on a radius substantially the same as that of shell 14. The horizontal distance between the convex side of the partition 20 and shell 14 is thereby made uniform on all lines parallel to the central radius of the partition and I have used such a space for the pass 22 thereby being enabled to build up the bundle T of units of uniform dimensions. As illustrated, the upper ends of the inlet sections 34 and 34a of the tubes connect to serpentine tube sections 36 which are bent back and forth in vertical planes on bends of substantially 180° curvature thereby forming a series of serially connected U loops, each serpentine section lying, as shown in Fig. 1, substantially in a vertical plane throughout. As appears fully from Figs. 1 and 3, the serpentine sections 36 are of substantially uniform size and extend the full horizontal distance between the partition 20 and shell 14 in pass 22. The sections 36 lie close together and fill the entire space of the pass with only sufficient clearance between the tubes for passage of steam or other fluid to be heated.

The segments 38 within the shell 14 lying at the ends of the partition 20 evidently will not accommodate serpentines of the same horizontal dimension as sections 36, and, in order to avoid special tube units for such segments, the pass 22 is spaced from the shell 14 along the vertical edges of the partition 20 by flat vertical plates such as 40 (Fig. 3). In order to prevent fluid to be heated from freely by-passing the tube bundle T through segments 38, each of such segments 50 is closed at its bottom by a plate 42 (Fig. 6). It is preferred also to close the tops of segments 38 by plates 42a (Fig. 2) so that any steam leaking into segments 38 cannot escape from them without passing through the heating pass 22. It has been found desirable moreover to divide plate 40 by a slip joint 41 to permit relative movement of the two parts of said plate. As shown, joint 41 runs parallel to the longitudinal axis of the exchanger 60 intermediate the joints between plate 40 and shell 14. Such a joint prevents undue stresses in the plate and its connections when different parts of the re heater are at different temperatures.

A feature of my invention whereby the

tubes may be readily inserted in and withdrawn from the heating pass of the exchanger is embodied in the apparatus of Fig. 1 in an arrangement comprising beams 44 whose ends rest in a recess 46 formed in the upper face of flange 48 near the upper end of shell 14. Depending from the beams 44 are hanger bars 48, to which the serpentines 36 are attached by U-clamps 50, (Fig. 5). As appears clearly in Fig. 5, two serpentines 36 are fixed to one hanger 48 thereby forming a unit for insertion into and removal from the re heater. At their lower ends, the tube units may rest upon cross beams 52 and the curved sections of the serpentines 36 are shown in Fig. 4 as braced against lateral movement or vibration by channels 54, welded to the inner face of shell 14. It will be seen that by removing the cover 56 of the shell and by disconnecting the tubes of a given unit from the headers 26 and 28, any unit can be easily taken out of the shell and afterward replaced in a reverse manner.

Another feature of the invention resides in the particular form of the elements of the tube bundle. For reasons not involved in the present invention, bifurcated tubes have been proposed for use in heat exchangers. I, therefore, have illustrated the serpentines of the tube bundles as formed of bifurcated tubes. In the arrangement illustrated in Figs. 1 to 6, the inlet sections 34, 34a of the tube units are of the single tube type, the inlet sections 34, 34a being bifurcated at 57 to form serpentines 36 the halves of which are reunited at 61 to form outlet sections 62 and 62a of the single tube type. However, to obtain the maximum heating surface in a given space with such an arrangement, I find it necessary that the inner bends 58 of the bifurcated tubes of the serpentines be formed by welding together the adjacent lengths or runs of tubing, such as 60, of a given half of a bifurcated tube. It has been found also that when using a maximum number of tubes in a given pass or space that it is difficult to provide room on headers of moderate size for making the connections between the heating tubes and the headers. In order further to provide space for attaching the tubes to the headers, tube sections 34 are attached to a header 26 in a row 64 which is spaced angularly from the row 65 along which the tube sections 34a are secured to the header. A similar arrangement is employed also for connecting tube sections 62 and 62a to header 28. Manhole structures 68 are provided in the bottoms of the exchangers and in the covers 56 thereof for permitting entering shells when desired.

In operation, steam to be reheated enters shell 14 at 16, passes up around and in contact with the heating coils of bundle T in pass 22, down the pass 24 and out through the outlet 18, the parasitic transfer of heat from steam in pass 24 to that in pass 22 is pre-

vented almost entirely by keeping the temperature of partition 20 substantially equal to that of the steam in pass 24 by heat from the tubes 34 and 34a arranged close to partition 20.

5 I claim:

1. A heat exchange apparatus comprising a shell, a partition in said shell defining a portion of the wall surface of a pass through the shell, a plurality of elements for conveying a heating fluid located in said pass, the inlet portions of said elements being disposed adjacent to said partition.

10 2. A heat exchange apparatus comprising a shell, a partition dividing said shell into two longitudinal passes, a plurality of elements for conveying a heating fluid located in one pass, the inlet portions of said elements lying adjacent to said partition along the major portion of its length.

20 3. A heat exchange apparatus comprising a cylinder shell, a partition dividing said shell into two longitudinal passes, said partition being transversely curved on substantially the same radius as the radius of the shell, whereby one pass of uniform width is formed between the partition and the wall of the shell, and a plurality of tubular heating elements located in said pass, each of said elements comprising a series of serially connected U-loops disposed transversely of said pass across its uniform width.

35 4. In a heat exchanger, the combination of a chamber, headers in said chamber, elements in said chamber having sections running adjacent the wall of said chamber and reversely curved sections substantially filling the cross-section of the chamber, detachable joints for connecting said elements to said headers, and means for supporting said elements in said chamber so arranged that the elements and supports may be removed from the chamber in individual units.

40 5. In a heat exchange apparatus, the combination of a chamber, headers in the lower part of said chamber, elements suspended from the upper portion of said chamber and having inlet sections running adjacent the wall thereof and reversely curved sections substantially filling the cross-section of the chamber, detachable joints for connecting said elements to said headers, and means for supporting said elements in said chamber so arranged that the elements and supports may be removed from the chamber in individual units.

45 6. A coil element for heat exchanger having single tube portions for connection to headers and a bifurcated intermediate serpentine portion, said serpentine portion comprising two parallel tubes winding back and forth and having reverse curves at which the tubes lie in the same plane, the inner one of a given pair of coplanar curves comprising 50 welded ends of adjacent tube runs.

7. A heat exchanger having a shell enclosing a heating pass, a plate connected to said shell along two opposed edges of the plate and separating said pass from a segmental space between the plate and shell, means closing the ends of said space, and a slip joint in said plate extending the length of the plate parallel to the axis of said pass.
